POPPET VALVE

Filed Aug. 25, 1924

INVENTOR.
Earle S. MacPherson

BY William H. Whitman

ATTORNEY.

UNITED STATES PATENT OFFICE.

EARLE S. MACPHERSON, OF DETROIT, MICHIGAN, ASSIGNOR TO HUPP MOTOR CAR CORPORATION, OF DETROIT, MICHIGAN, A CORPORATION OF VIRGINIA.

POPPET VALVE.

Application filed August 25, 1924. Serial No. 734,090.

The invention relates to poppet valves and has for its main object the provision of an improved poppet valve having provision for facilitating the adjustment of its abutment member. Another object is the provision of means upon the valve stem and engageable by a wrench for holding the valve stem from rotation during rotation of the abutment member which is threaded upon the valve stem. A further object is the provision of a valve spring retainer engageable by a wrench and nonrotatably connected to the valve stem for holding the latter, from rotation during rotation of its abutment member.

With these as well as other objects in view the invention resides in the novel features of construction and combinations and arrangements of parts as more fully herein-after set forth.

In the drawings:—

Figure 1 is a cross section through a portion of an internal combustion engine and showing my improved poppet valve;

Figure 2 is a cross section on the line 2—2 of Figure 1.

1 is the poppet valve and 2 the valve stem having its lower end portion threaded and provided with the longitudinally extending groove 3 which preferably terminates above the threads. 4 is a nut threaded upon the lower end portion of the valve stem 2 and forming the abutment member for engagement by suitable valve actuating means, such as the lever 5. 6 is a lock nut also threaded upon the lower end portion of the valve stem and engageable with the upper end of the nut 4. 7 is the retainer for the valve spring 8, this retainer being preferably formed of sheet metal and having the integral inwardly extending key or projection 9 slidably engageable in the groove 3 of the valve stem to non-rotatably connect the retainer to the valve stem. This retainer has provision for engagement by a wrench which consists preferably of the peripherally spaced upwardly extending projections 10.

With this arrangement adjustment of the nut or abutment member 4 may be readily accomplished by first applying wrenches to the nut or abutment member 4 and lock nut

6 and then moving the lock nut 6 longitudinally upward along the valve stem 2 by rotating the same and holding the valve stem from rotation by means of a wrench applied to the valve spring retainer 7. Then the nut or abutment member 4 may be rotated to the desired position longitudinally of the valve stem 2 while holding the latter stationary through a wrench applied to the valve spring retainer, after which the lock nut 6 is tightened down upon the nut or abutment member 4.

What I claim as my invention is:

1. In a poppet valve, the combination with the valve and its stem, of an abutment member threaded upon said stem, a member upon said stem engageable by a wrench for holding said stem from rotation during rotation of said abutment member and a locking element embracing the stem for locking the abutment member in its adjusted position.

2. In a poppet valve, the combination with the valve and its stem, of an abutment member threaded upon said stem and a second member slidably longitudinally of said stem but nonrotatably connected thereto for engagement by a wrench to hold said stem from rotation during rotation of said abutment member and a locking element engageable with the stem and the abutment member.

3. In a poppet valve, the combination with the valve and its stem, of a nut threaded upon said stem, a lock nut also threaded upon said stem and a member upon said stem engageable by a wrench for holding said stem from rotation during rotation of either of said nuts.

4. In a poppet valve, the combination with the valve and its stem, of a nut threaded upon said stem, a lock nut threaded upon said stem and a valve spring retainer splined upon said stem and having provision for engagement by a wrench to hold said stem from rotation during rotation of either of said nuts.

5. In a valve construction, the combination with a valve and its stem, of a spring encircling said stem and a valve spring retainer engageable with said stem and spring, said valve spring retainer being constructed of sheet metal and formed with projections

extending from the main body portion of the spring retainer for engagement by a wrench.

6. In a valve construction, the combination with a valve and its stem, of a spring encircling said stem and a valve spring retainer engageable with said stem and spring,

said valve spring retainer being constructed of sheet metal and formed with projections bent at right angles with the main body portion of the spring retainer for engagement by a wrench.

In testimony whereof I affix my signature.
EARLE S. MACPHERSON.
